[57] CLAIM

The ornamental design for a surface for a front panel for a video editing controller, as shown and described.

DESCRIPTION

FIG. 1 is a front elevational view of a surface for a front panel for a video editing controller showing my new design;

FIG. 2 is a bottom plan view thereof;

FIG. 3 is a top plan view thereof;

FIG. 4 is a right side elevational view thereof; and

FIG. 5 is a left side elevational view thereof.

The broken line showing of the video editing controller housing is for illustrative purposes only and forms no part of the claimed design.

FIG. 1

FIG. 2

FIG. 3

FIG. 4

FIG. 5
